US00D997551S

(12) **United States Design Patent** (10) Patent No.: **US D997,551 S**
(45) Date of Patent: **** Sep. 5, 2023**

(54) **EARPHONE CASE**

(71) Applicant: **Daopeng Zhong**, Shenzhen (CN)

(72) Inventor: **Daopeng Zhong**, Shenzhen (CN)

(**) Term: **15 Years**

(21) Appl. No.: **29/801,224**

(22) Filed: **Jul. 28, 2021**

(30) **Foreign Application Priority Data**

Feb. 3, 2021 (CN) 202130080100.0

(51) **LOC (14) Cl.** **03-01**

(52) **U.S. Cl.**

USPC **D3/273**; D3/218; D3/302

(57) **CLAIM**

The ornamental design for an earphone case, as shown and described.

DESCRIPTION

FIG. 1 is a front, bottom perspective view of an earphone case showing my new design;

FIG. 2 is a rear, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the figures depict the portions of an earphone case that form no part of the claimed design.

1 Claim, 8 Drawing Sheets
